UNITED STATES PATENT OFFICE.

AUGUSTUS C. SAXTON, OF NEW YORK, N. Y.

SAW-SETTING MACHINE.

SPECIFICATION forming part of Letters Patent No. 661,647, dated November 13, 1900.

Application filed November 2, 1899. Serial No. 735,579. (No model.)

To all whom it may concern:

Be it known that I, AUGUSTUS C. SAXTON, a citizen of the United States, and a resident of No. 371 Pearl street, in the borough of Brooklyn, city of New York, county of Kings, and State of New York, have invented a new and Improved Saw-Setting Machine, of which the following is a specification.

The general features of my invention are as follows: The saw-blade, having teeth cut on it, is clamped in a device which I call a "traveling carriage," the toothed edge of the blade projecting above the carriage. A feeding apparatus, automatically actuated by the machine, feeds the carriage and the saw carried by it to the machine by a step-by-step movement, two teeth at a time. In its transit the teeth of the saw come opposite certain fixed anvils, opposite to which anvils are automatically-actuated plungers which are struck by spring-actuated hammers, one of them adapted to act upon the teeth to be set to the left, the other upon the teeth to be set to the right, and the machine is so timed that the feeding of the saw-blade and the setting of the teeth follow in exceedingly-rapid succession, so that it takes a very brief time only to set a saw.

Referring to the drawings thereof, Figure 1 illustrates a plan view of the machine. Fig. 2 illustrates an elevation, partly in section, taken on the line 1 1 of Fig. 1. Fig. 3 is an end view taken at the front of the machine. Fig. 4 illustrates a detail of one of the anvils and its plunger. Fig. 5. illustrates a detail in section of one of the racks which actuate the hammers.

A is the main shaft of the machine, upon which are mounted fast and loose pulleys B B, as usual.

C is the driving-belt.

D are casings, having hubs E E, which are set upon the shaft A.

F F' are cams connected with rods G, which by wrist-pins H H are connected to vertically-sliding racks I I. These racks engage with pinions J, loosely set upon shafts K.

L L are arms connected, respectively, to the pinions J, which turn with them loosely upon the shafts K.

M M are pawls pivoted to the arms L, each actuated by a spring N, and each has near its extremity a pin O.

P P are the hammers, made somewhat in the form of segments, each provided with a notch or detent Q. The hammers are fast upon the shafts K.

R R are two cam-like tripping devices for the pawls M M, respectively, the pins O upon which engage with the inclined surfaces S S thereof, as hereinafter explained. The tripping devices R R are rigidly attached to some part of the machine.

T T are two cases, within each of which is a somewhat strong coiled spring U, one end of which engages with the shaft K, as shown, and the other end with the casing T.

V V are the plungers. They pass through suitable openings made in studs W W on the machine and are actuated, respectively, by springs Y Y. These springs at one end Z abut against one of the studs W W and are free at their other ends, which engage, respectively, with an enlarged head on the plungers V, so that when the plungers are forced inwardly by the blow of the hammers P, compressing the spring, and the pressure is relieved the spring will automatically return them to their primary location.

a a (see Fig. 1) are the two anvils. They are held in place by a clamping-plate b b and set-nut c c, and are so arranged as to be presented directly opposite the ends of the plungers. In Fig. 4 I show a detail of the arrangement of the anvils and plungers. The anvils a are ground true on the face, but the top and bottom edges are ground on a bevel, as shown at d d, and the face of the plunger V is ground to such an angle as to accurately engage with the beveled edges d d of the anvils to produce the desired set and upsetting or flattening of the teeth.

The saw and its carriage are best shown in Fig. 2.

e is the saw-blade, and f the carriage, provided with feeding-teeth g on its upper edge.

h h are set-screws upon which the saw-blade is supported and adjusted in the carriage. They are threaded into the two parts of the carriage, and their milled heads are accessible through openings, as shown, made in the plates which form the carriage, so that they can be readily manipulated by the finger and thumb to regulate the vertical position of the saw within the carriage.

h' h' h' are some of the screws which hold together the two parts of the carriage.

h² h² are bolts which are attached to the table *h³* of the machine, upon which the saw-carriage rests. These bolts pass downwardly through the solid immovable frame of the machine, as shown, and have heads *h⁴* on their ends.

h⁵ h⁵ are springs which encircle the bolts *h²* and abut at one end against the frame of the machine and at the other against the heads of the bolts.

h⁶ represents screw-bolts which are threaded into the frame of the machine, as shown, and rest at their upper ends against the under side of the table *h³*. By these means, in a manner well known, the table *h³*, carrying the saw-carriage upon it, can be adjusted vertically with great exactness to give more or less set to the teeth of the saw, as may be desired. The springs *h⁵*, acting through the bolts *h²*, tend to pull the table *h³* downwardly, and the threaded bolts *h⁶* afford means for determining the elevation of the table.

25 The feeding mechanism consists of a fork-shaped piece *i*, which engages with an eccentric *j* upon the main shaft *A*, and to the forked piece *i* is connected by suitable adjusting devices *k* a rod *m*, which is pivoted to a lever *n*, to the other end of which is pivoted a feeding-pawl *o*, which in the present instance acts by gravity, engaging with the teeth *g* on the carriage which holds the saw.

30 *p* is a retracting-spring for the forked piece *i* and coacting parts, whereby it is normally held in engagement with the eccentric *j*, and also after each forward impulse the feeding-pawl *o* is returned to primary position by reason of the rocking of the lever *n*, occasioned 40 by the spring *p*.

35 In Fig. 5 I show a detail of the construction of the racks *I*. This figure is taken on the line *x x* in Fig. 2 looking in the direction of the arrow. The edges of the racks are shown 45 as dovetailed, each sliding in a correspondingly-shaped slideway made between the parts *q q* of the main frame and a stay-piece *r*, attached to the frame *q* by bolts *s* or equivalent device.

40 The operation of the apparatus is as follows: The saw in its carriage is introduced at the front end of the machine—that is to say, at the right-hand side, as shown in Fig. 2. The carriage, with the saw-blade properly adjusted 55 upon it, is pushed into the machine through the slideway provided for it (shown in Fig. 3) until the blade reaches the point where the setting operation may be performed upon it. It is sometimes desirable to lift the feeding-

50 pawl *o* by hand during the introduction of the carriage, so that it may be pushed in until the saw-blade reaches the plungers, thus saving time. When this point has been reached, the pawl is allowed to engage with the teeth 65 of the carriage and the machine is started. At each revolution of the main shaft the feeding device propels the carriage a distance

equal to two teeth. Suitable devices are provided for the adjustment of the feeding mechanism, so that the machine will be adapted to set saws having teeth of different sizes. At each revolution of the main shaft and concurrently with the feeding operation the cams *F F'* vertically reciprocate the racks *I I*, which in turn rotate the pinions *J J*, whereby the 70 pawls *M M* move to the right and left, as indicated by the arrows in Fig. 3, swinging outwardly the two hammers *P P*, thereby putting the springs *U U* under tension. The pawls carry the hammers outwardly until the pins *O O* engage with the inclined surfaces *S S* of the respective tripping-plates *R R*, whereupon the pawls are tripped and the hammers *P* released and thrown by the springs *U U*, each delivering a blow upon the head of its plunger *V V*, 85 respectively. The forward ends of the plungers are driven inwardly, each engaging with the appropriate tooth on the saw, setting it against the anvil, (which is immediately behind it,) and thereupon the springs *Y Y* return the plungers to normal position. By the continued rotation of the main shaft the eccentrics bring back the pawls *M* and arms *L* to primary position ready for another operation. 90

The above-stated operation of the parts is 95 repeated with great rapidity, and the work performed is of a remarkably accurate and satisfactory character.

It will be obvious to those who are familiar with this art that many modifications may be made in the details of construction of the parts without departing from the essentials of the invention. I therefore do not limit myself to such details.

I claim—

1. In a saw-setting machine the combination of a movable carriage within which the saw is clamped, intermittently-acting feeding devices which engage with the carriage, a pair of independently-acting and spring-actuated hammers, which operate in reverse directions, plungers adapted to be engaged by the hammers, and anvils to resist the thrust of the plungers, for the purposes set forth. 110

2. In a saw-setting machine the combination of a movable carriage within which the saw is clamped, intermittently-acting feeding devices which engage with the carriage, two independently-acting and spring-actuated hammers, one presented to the right and the other to the left, right and left plungers adapted to be engaged by the hammers, and right and left anvils adapted to resist the thrust of the plungers, the faces of the anvils 120 being beveled opposite the teeth to set the teeth to the right and left respectively, for the purposes set forth.

3. In a saw-setting machine the combination of a movable saw-clamping carriage, means to adjust the saw within the carriage, intermittently-acting feeding devices for the carriage, a pair of independently-acting and spring-actuated hammers, the parts being so 130

arranged that the feeding is effected during the time the springs of the hammers are put under tension, and the hammers act during the time the feeding devices are recovering; 5 plungers each provided with a retracted spring adapted to be engaged by the hammers, and anvils to resist the thrust of the plungers, for the purposes set forth.

4. In a saw-setting machine the combination of a carriage for the support of the saw, feeding devices adapted to engage with the carriage, reciprocating racks which engage respectively with pinions, oscillating hammers, means whereby the hammers are actuated by the racks and pinions, springs put under tension by the movement of the hammers respectively, plungers which receive the stroke of the hammers, and springs for the retraction of the plungers, for the purposes set forth.

5. In a saw-setting machine the combination of independently-acting oscillating hammers mounted upon shafts, separate springs, each connected with its respective hammer 25 and put under tension by their movement respectively, pawls intermittently actuated by the machine for moving the hammers and giving tension to the springs, devices immovable on the machine against which the pawls 30 strike and by which they are tripped for the release of the hammers, plungers adapted to receive the stroke of the hammers, and anvils adapted to resist the thrust of the plungers, for the purposes set forth.

35 6. In a saw-setting machine the combination of a shaft, cams mounted upon the shaft, racks connected with said cams, pinions which engage said racks, pawls carried by the pinions, oscillating hammers engaged by the 40 pawls, means to trip the pawls, springs put under tension by the movement of the hammers, plungers to receive the stroke of the hammers, and anvils to resist the thrust of the plungers, for the purposes set forth.

45 7. A movable carriage for supporting a saw-

blade composed of two plates, separate from other parts of the machine and adapted to clamp the blade between them, means such as screws carried by the plates, whereby they may be clamped together and adjustable devices located between the plates for determining the vertical position of the saw-blade between the two parts of the carriage, for the purposes set forth. 50

8. A carriage for supporting a saw-blade 55 composed of two plates adapted to clamp the blade between them, adjustable devices located between the plates for determining the vertical position of the saw-blade within the carriage, and detents or teeth on one of said 60 plates whereby the carriage and the saw-blade may be fed through the machine, for the purposes set forth.

9. The combination of a table or plate upon which the saw-carrying device rests, said table being not shorter than the saw-blade, adjusting-screws threaded into the frame of the machine whereby the respective ends of the table may be vertically and independently adjusted, and springs connected with the said 65 table which normally pull the same downwardly, for the purposes set forth.

10. The combination of a table or plate upon which the saw-carrying device rests, said table being not shorter than the saw-blade, adjusting-screws threaded into the frame of the machine whereby the respective ends of the table may be vertically adjusted, downwardly-extending headed bolts connected with the 70 table, and springs encircling the bolts, engaging with the heads thereof at one end and against some immovable part of the machine at the other end, for the purposes set forth.

Signed at New York, in the county of New York and State of New York, this 30th day 85 of October, A. D. 1899.

AUGUSTUS C. SAXTON.
